CLAUDE, OF PARIS, FRANCE

APPARATUS FOR CONSERVING AND VAPORIZING LIQUEFIED GASES

Application filed July 29, 1929, Serial No. 381,958, and in France July 31, 1928.

The present invention relates to improvements in storing and vaporizing apparatus for liquefied gases and more particularly to devices for storing and transporting gases at low temperature and to apparatus for vaporizing said gases, under pressure, by means of a liquid pump and a vaporizer for the liquefied gases.

One of the objects of the invention comprises means to maintain automatically within the insulating covering surrounding the liquefied gases, an atmosphere excluding the outside air and dampness and the pressure of which is comprised within predetermined limits.

Another object of the invention resides in the provision of means to insure the correct functioning of the liquid pump while preventing, during idle periods, the condensation of the outside air humidity upon the parts in contact therewith and also upon the walls of the tank wherein the pump is disposed.

The invention has for an object also to improve the working of the vaporizer wherein the liquefied gas is vaporized by means of a pump circulating the liquefied gas upwardly therein and insuring an efficient exchange of heat between the liquefied gas and the fluid adapted to vaporize the same.

Other objects of the invention will be apparent and described in the following specification and drawing, wherein a schematic representation of an insulation is shown particularly adapted to the vaporization of liquefied oxygen.

The liquefied gas is contained in container 8 insulated from the outside envelope 9 by a lining 10, for example, magnesium carbonate. Said container 8 is secured to the outside envelope 9 by means of suspension chains 3 and 3' (for purposes of clarity, only one chain of each kind has been shown on the drawing). The chains 3', the supports of which to the envelope 9 are situated below the securing points on the container 8 have for an object to prevent that the same be lifted by the extreme fluidity of the insulating matter when said container is empty.

The envelope 9 is provided with a safety

valve 30 and a metal-foil disk 31 adapted to be fractured when the internal pressure reaches a given limit. Furthermore, part of the envelope, at the top thereof, affects the shape of a disk 1; said disk being attached to the sheet metal constituting the envelope 9 by a thin rubber diaphragm 32. When, due to an accident, a leak occurs in the receiver 8 whereby the liquefied gas is absorbed by the insulating matter and vaporized thereby, the pressure quickly rises inside the envelope 9. Accordingly, the diaphragm 32 is torn and the disk 31 is free to rise and permit the escape of a great quantity of the imprisoned gas and also of part of the insulating material as the case may be.

A duct 11 feeds into the insulating matter a certain quantity of the gas evaporated in the liquid container whereby a certain pressure always exists therein. In said duct, a valve 2 is inserted which is regulated to be open when the pressure of the gas within the insulating lining is below a given limit, 5 cm. of water for example. Whenever the pressure in the insulating lining rises above this value, the valve is closed and the circulation of gas interrupted. Therefore, there is always tolerated in the lining a very light pressure.

On the duct 11, after the valve 2, a branch 12 is connected whereupon a second valve 2' is inserted and which is regulated up to 10 cm. of water. If the pressure increases over this value, the valve 2' opens and the gas contained in the lining escapes to the atmosphere through 13, whenever this is produced for different reasons, for instance, when the receiver 8 is empty of liquid.

It follows, therefore, that due to the use of the valves 2 and 2' a pressure is always maintained in the insulating lining and which is automatically maintained between 5 and 10 cm. of water. Of course, the valve 2' can be replaced by a mercury valve.

The liquefied gas pump 14 is situated in a tank 15 lined also with insulating material and connected to the liquefied gas receiver by the pipe 16; the inlet being through a port 35 and the exhaust through a ball valve 36. There is maintained in the tank 15, during

operation of the pump, a constant level by the following means: At a certain height below the lowest level to be maintained, a certain part of the liquid is branched at 17 which upon being heated by the surrounding air is vaporized and actuates a valve 4 adapted to open or close the inlet of liquid from the duct 16 by means of a system of levers actuating a needle valve 19 according to the pressure.

The tank 15 is adapted to be emptied during the idle periods of the pump. It has been found that condensation of moisture inside said tank should be prevented at all 18 cost together with all the cold parts of the apparatus in contact with the outside atmosphere. To that end, a duct 5 is provided which feeds a part of the evaporated gas from the receiver 8 to the bottom of the tank 15 and around the pump 14; more particularly, it is necessary that the gas be circulated in the space 33 around the piston rod to prevent the condensation of dampness upon said parts. In the event said circulation of gas 25 be prevented due to the absence of liquefied gas in the receiver 8, the various parts which are in contact with the outside atmosphere are treated or made of rustless metal or steel, Monel metal or any other metals which 30 are rendered rustless by known treatments, such as nitrogen hardening, parkerizing or chromium plating.

The lubrication of the metallic parts of the pump is effectuated in manufacturing 35 said parts of metals or alloys having a considerable hardness by means of nitrogen case-hardening in order to reduce as much as possible the co-efficients of friction.

The liquefied gas is circulated by the pump 40 14 through a conduit 20 into a vaporizer which is submerged in the water of a container 21 and which is constituted by a bunch of coils 7 connected in parallel. The liquefied gas travels through said coils downward- 45 ly and absorbs the heat of the water whereby the gas is vaporized. This system of circulation of the liquefied gas enables one to use the minimum amount of water to vaporize a given amount of liquid. As the coldest 50 portions of the water in the vessel which contains the vaporizing coil are at the upper part of this vessel and as they are simultaneously the lightest portions, no circulation of water from the top to the bottom of the vessel is 55 caused by the difference in the density of said water; consequently, a total and rapid freezing of the water contained in the vessel is avoided and, therefore the efficiency of the apparatus is not diminished, whilst such efficiency would be diminished in the case of 60 total and rapid freezing of water, since in this latter case the vaporized gas would leave the vaporizer in a too cold state. On the contrary, the ice which surrounds the upper 65 part of the spires of the vaporizing coils be-

comes cooled by the very cold liquefied gas which enters at the top of the vaporizing coils, whereas the vaporized gas leaves the apparatus at the temperature of the water situated in the bottom of the vessel, about 70 +4° C. n.

The produced gas under pressure reaches the apparatus of consumption through 22 and the branch 23 opening at the bottom of the container 21 whereby part of the gas is 75 fed into said container to agitate the water thereof in order that the temperature throughout its mass be adjusted at a constant level; the said gas necessary to agitate the water is regulated by a valve 24 which, by 80 the way, may be replaced by an expansion valve.

Finally, at the start of the conduit 20, near the pump, a coil 6 is mounted having a single tube of copper of internal diameter as large 85 as the mechanical resistance and manufacturing limitations permit. This coil is placed in contact with the atmosphere and closed at 34; later, the volume of said coil is gradually filled by compressed gas resulting from the 90 vaporization of the liquid occupying a good portion of said coil 6. The object of the coil is to provide a gas cushion to dampen the working of the pump.

What I claim is:

1. An apparatus for conserving liquefied gases, which comprises a liquid container, an exterior sheath and insulating material therebetween, means for automatically admitting up to a predetermined pressure a part of the 100 evaporated gas to the space between the container and exterior sheath and means for preventing the gas pressure in the insulating material to exceed a certain limit and for allowing the gas in the insulating material to 105 escape outwards, when the pressure of this gas has reached the said limit.

2. An apparatus for delivering liquefied gases which comprises a liquid container, a pump, an intermediate vat, means for conducting a part of the liquid from said vat in relatively warm zones and for vaporizing it under pressure and means for controlling by said pressure the arrival of liquid to the 110 said vat.

3. An apparatus for delivering liquefied gases which comprises a pump, a vat and means for sweeping the parts of apparatus liable to be in contact with the atmospheric air by a flow of evaporated gas.

4. An apparatus for containing liquefied gases which comprises an internal liquid container, an outer sheath, insulating material therebetween, a separate member forming a part of the outer sheath and frangible means 120 for attaching said member to said sheath.

5. An apparatus for vaporizing under pressure liquefied gases which comprises a pump for liquefied gases, a container for a heating medium, heat exchange means sub- 125 130

merged in the said heating medium and in which the liquefied gas forced by the said pump becomes vaporized under pressure, means for diverting a part of this gas under pressure and for conducting it into the heating medium which surrounds the said heat exchange means.

6. An apparatus for delivering liquefied gases which comprises a pump, a conduit 10 deriving a part of the delivered liquefied gas branched off on the delivery pipe of the pump between the pump and the vaporizer, a closed vessel in connection with said conduit and situated in relatively warm zones in order 15 to vaporize under pressure the derived part of the liquefied gas, the gas under pressure in said closed vessel constituting a gas cushion damping the working of the pump.

7. An apparatus for vaporizing liquefied 20 gases which comprises a container, a determined bulk of noncirculating water enclosed in said container, exchange means immersed in the said bulk of water and connected at their upper end to a distributing pipe for 25 liquefied gas and at their lower end to a discharge pipe for vaporized gas.

8. An apparatus for vaporizing liquefied gases which comprises a container, a determined bulk of noncirculating water enclosed 30 in said container, several sinuous tubes in parallel situated in vertical planes, immersed in the said bulk of water and simultaneously traversed by the liquefied gas from their upper end connected to a distributing pipe for 35 liquefied gas to their lower end connected to a discharge pipe for vaporized gas.

In witness whereof I have hereunto set my hand.

CHARLES PICARD.
